UNITED STATES PATENT OFFICE.

HALVER R. STRAIGHT, OF ADEL, IOWA.

APPARATUS FOR DISTILLING OIL FROM OIL-BEARING SHALES.

1,323,204.

Specification of Letters Patent. Patented Nov. 25, 1919.

Application filed July 31, 1918. Serial No. 247,693.

To all whom it may concern:

Be it known that I, HALVER RUFUS STRAIGHT, a citizen of the United States, and resident of Adel, in the county of Dallas 5 and State of Iowa, have invented a certain new and useful Apparatus for Distilling Oil from Oil-Bearing Shales, of which the following is a specification.

The object of my invention is to provide 10 an apparatus of simple, durable and inexpensive construction, for distilling oil from oil bearing shales.

A further object is to provide an apparatus of this kind whereby large quantities of 15 shale may be subjected to the necessary amount of heat during the necessary length of time for vaporizing the oil product in a minimum of time, whereby a relatively inexpensive apparatus is provided that will 20 treat relatively large quantities of shale in a minimum of time.

A further object is to provide a device 25 of this class in which steam may be introduced into the shale at proper times for assisting in the distillation and separation of the vapors, and in which the shale may be repeatedly turned over or agitated to assist the escape of the vapors from the mass of shale.

30 A further object is to provide an apparatus of this class in which the oil bearing shales may be continuously moved in wide, thin layers over a substantially horizontally arranged heating chamber, through a series 35 of vapor chambers above the shale so that the vapor when once released from the shale will immediately pass into a vapor chamber from which it may be drawn to a suitable condenser and container therefor, and main- 40 tained separated from the vapors later released, and whereby the separation of the vapors from the shale is accomplished rapidly and with a maximum of efficiency.

45 A further object is to provide an im- proved means for conveying shale in a thin, wide layer without permitting the flame from the heater to penetrate through the layer of shale or to become commingled with the vapors arising from the shale.

50 A further object is to provide an im- proved car device for carrying the thin layer of shale through the heated areas of the apparatus and for maintaining the shale carried thereby at a uniform thickness.

55 A further object is to provide improved

means for advancing the cars through the heated areas of the apparatus, and to maintain them in close contact with each other during their travel through the heated areas.

A further object is to provide improved 60 means for returning the cars after they have discharged their contents, back to the starting point to receive a new load of shale.

A further object is to provide means for applying a continuous yielding pressure to 65 the cars entering the heated areas, and to hold them firmly in contact with the other cars.

A further object is to provide an im- 70 proved form of steam injector device for the purpose of subjecting substantially all of the shale on the cars to the action of the steam, and for compelling the steam, or the major portion of it, to travel through the thin layer of shale uniformly before escap- 75 ing through the top of the shale into the vapor chambers.

A further object is to provide improved 80 means for sealing the vapor chamber from the combustion chamber at all times during the travel of the shale bearing cars, to thereby avoid the possibility of the flame from the combustion chamber igniting the vapors.

My invention consists in the construction, arrangement and combination of the various 85 parts of the apparatus, whereby the objects contemplated are attained, as hereinafter more fully set forth, pointed out in my claims and illustrated in the accompanying drawings, in which:

90 Figure 1 shows a vertical, central, longitudinal, sectional view of the front or loading end of an apparatus embodying my invention.

Fig. 2 shows a like view of the central 95 portion of the same.

Fig. 3 shows a like view of the rear or discharge end portion of the same.

Fig. 4 shows a transverse, sectional view 100 on the line 4—4 of Fig. 2.

Fig. 5 shows an end elevation, partly in section, illustrating the shale containing hopper and the means for delivering material therefrom to the cars as they enter the distilling chamber.

Fig. 6 shows a detail sectional view, illustrating the friction clutch device applied to the axle of the means for pushing the cars into the receiving chamber beneath the hopper.

110

Fig. 7 shows a detail, side elevation, partly in section, illustrating the means for coupling together the sand seals of the shale carrying cars.

5 Fig. 8 shows a detail top or plan view of the steam nozzle device for injecting steam under the layer of shale.

Fig. 9 shows a side elevation of same.

10 Fig. 10 shows an enlarged sectional view on the line 10—10 of Fig. 9.

Fig. 11 shows an enlarged, detail, sectional view, illustrating the sand seal between the ends of the two adjoining shale carrying cars.

15 Fig. 12 shows a sectional view illustrating the shale leveling and gas sealing device for the receiving end of the vapor chamber, and

20 Fig. 13 shows a side elevation of one of the shale stirring plows.

Referring to the accompanying drawings, I have used the reference numeral 10 to indicate generally the base of the apparatus, having upright side walls 11 and the top 25 arch 12 preferably made, or at least lined, with fire brick.

At about the horizontal center of the chamber thus formed are the recesses 13, containing the rails 14, and upon these rails 30 are mounted the shale carrying cars, which, together with the sand sealing devices, constitute a sort of horizontally arranged partition separating the combustion chamber from the vapor chamber. The combustion 35 chamber is indicated generally by the numeral 15, and the vapor chamber is indicated generally by the numeral 16. Within the combustion chamber is a series of gas jets 17 or other suitable means for supplying heat.

The shale carrying cars each comprise a flat base member 18 preferably provided with ribs 19 on its upper surface for strengthening purposes. At the sides of the 45 base member 18 are the upright sides 20 for forming a container for the shale. These sides preferably project downwardly a considerable distance below the bottom 18, and these projecting members are indicated by 50 the numeral 21, and are for the purpose of forming a sand seal. Directly beneath these projecting members 21 is a longitudinally arranged recess 22 in the side wall, which recess is preferably filled with sand 55 or the like to receive the sealing members 21.

On the sides of the shale carrying cars thus formed are the flanged supporting wheels 23 to travel upon the rails 14.

At one end of each car is a trough-shaped 60 sealing member 25, and at the other end a downwardly extending coacting sealing member 26. The trough-shaped member is filled with a sealing material, such as sand, and the other member enters it, as shown in 65 Fig. 11, thus preventing the entrance of

flame to the spaces between the ends of the cars.

For the purpose of preventing the passage of flame from the combustion chamber into the vapor chamber, and also for the purpose 70 of preventing the vapor from surrounding the walls and entering the sand seal at the sides of the cars, I have provided plates 27 fixed at their upper ends to the walls 11 and extended downwardly and yieldingly engaging the inner surfaces of the upright sides of the cars, as clearly shown in Fig. 4.

For the purpose of loading the shale carrying cars with a layer of shale of uniform depth, I have provided a suitable hopper 28 80 arranged beneath a railway track 29, which hopper is provided with downwardly and inwardly inclined sides 30 extended to points just inside of the sides of the cars. On the car receiving end of the hopper is an upright 85 partition member 31, with its lower end extended downwardly to a point flush with the tops of the sides of the cars, and on the other side of the hopper member adjacent to the vapor chamber, is a wall 32.

Beneath this wall 32 is a shale leveling and gas sealing device illustrated in detail in Fig. 12. This device comprises a metal plate 33 extended downwardly and forwardly to a point just over the top of the shale carrying cars, and on the interior of the vapor chamber is an apron 34 hinged or flexibly secured at its forward upper end to the wall and extended downwardly and designed to rest upon the shale carried by the car. Hence, by having the device for leveling off the top of the shale and then an apron for lying flat against the level portion of the shale, the escape of vapor at this point is substantially prevented.

To provide means for preventing the escape of heat from the receiving end of the combustion chamber, I have provided a flat metal plate 35 extended in a substantially horizontal direction and designed to project 110 under and contact with two of the sand sealing troughs of two adjacent cars. This plate is held upwardly into yielding contact with these sealing troughs by means of a weight 36, the plate being pivotally supported upon a T-beam 37 resting on the wall 38.

The products of combustion, after passing under the shale carrying cars, is discharged through the transverse flue 39 to a suitable 120 stack.

To provide for forcing the shale carrying cars under the hopper to receive a load of shale, I have provided the following mechanism, illustrated principally in Figs. 1, 6 125 and 7. The numeral 40 indicates an inclined track down which the cars are delivered in the manner hereinafter to be described. At the lower end of this inclined track is a car-advancing mechanism, comprising two 130

parallel shafts 41 and 42 provided with sprocket wheels 43 over which is passed a sprocket chain 44 having lugs 45 thereon designed to engage the sand seal troughs 25 5 of the shale carrying cars. This shaft 42 is driven by means of the large pulley 46 loosely mounted on the shaft and provided with a cone friction drive device 47, the friction cone being yieldingly held by a spring 10 48 in engagement with the pulley 46. By this arrangement it will be seen that a constant pressure is applied to the driving shaft 42, and if the shaft 42 cannot turn then the pulley may slip on the friction 15 cone. Said pulley is driven by a belt 49, preferably from a motor 50 or other source of power.

Located in the inclined track 40 adjacent to its lower end, is a lug 51, shown in Fig. 20 7, which lug serves the purpose of engaging the front wheels of a shale carrying car and elevating the entire car above the track far enough to permit the sand sealing member 26 to enter the trough 25 of the adjacent 25 car. Then after the car passes over the lug 51 the sand seal device will remain in a sealed position throughout the rest of the travel of the car through the apparatus.

For the purpose of holding all of the cars 30 within the combustion chamber in position firmly against each other, and for preventing any of the cars from separating, I have provided at the discharge end thereof a device comprising two parallel shafts 52 and 53 provided with sprocket wheels 54, over which is passed a sprocket chain 55 having lugs 56 designed to engage the sand sealing troughs of the cars. This device is driven by means of a large sprocket wheel 57 on 40 the shaft 53, connected by a sprocket chain 58 with a sprocket wheel 59 on the shaft 60, which shaft 60 is driven by a sprocket wheel 61 thereon, connected with a sprocket chain 62 which is driven in turn from a power 45 shaft 63.

By this arrangement the movement of the shale bearing cars through the device is accurately timed, and if it is desired to have the cars move faster or slower, it may be 50 regulated by changing the speed of the shaft 63 in any suitable manner.

Directly in the rear of the said retarding device is a refuse discharge hopper 64 arranged to discharge its contents upon a belt 55 conveyer device 65 for removing the refuse to a suitable point of discharge. The track on which the shale bearing cars travel is curved downwardly directly above the hopper 63 at 66, and then upwardly over the inclined frame 67. This curve in the track at 66 provides means whereby the trough-shaped portion of the sand seal on each car becomes automatically detached from the other sealing member, and the cars are then 60 65 inclined upwardly at a steep enough angle

to cause the contents of each car to discharge into the hopper 64, the position of the car at this point being illustrated in Fig. 3.

For carrying the cars up the inclined frame 67, I have provided a sprocket chain 68 traveling over the sprocket wheels 69 and 70. The sprocket wheel 69 is loose on the shaft 68, and the sprocket wheel 70 is fixed to a shaft 71, which shaft is driven by a motor 72 through a belt and pulley device 75 73, running at a comparatively high speed, so that as soon as each car is discharged from the retarding device at the discharge end of the combustion chamber, it is immediately disconnected from the adjacent car 80 and rapidly carried up the incline. At the top of the incline the lug 71 is withdrawn from the car, and then the car is free to run down the incline by gravity. At a point some distance below the top of the incline 85 67 are the hinged track sections 74, which are moved upwardly out of the way by an ascending car, and then dropped by gravity to the position shown in Fig. 3, so that as soon as the car is released it will travel downwardly over the incline and then over the hinged track sections 74 upon the inclined track 75, which returns the car by gravity to the receiving end of the combustion chamber.

For the purpose of permitting the returning car to travel in a straight line, I have provided in the hopper 28 a recess or opening indicated by the numeral 76 in Fig. 5, and at the forward end of the inclined track 75 is another hinged track section 77, normally held upwardly by a spring 78. The weight of a car striking this track section 77 moves it downwardly until the car can pass upon the inclined track 40, and as soon as the car passes over the hinged track section the spring 78 will elevate it, so that the returning car will run up the inclined track 40 to the spring bumper 79 and then return by gravity to the car pushing device for 100 forcing the cars under the shale containing hopper.

At the discharge end of the combustion and vapor chambers is a gas sealing device 80, similar to the gas sealing device shown 115 in Fig. 12.

During the time that the shale is being subjected to heat it is desirable to keep it constantly stirred so that the vapors may readily arise from it, and for this purpose 120 I have provided within the vapor chamber a series of cross pieces 81, each of which is provided with a number of uprights 82 secured thereto. On the lower end of each upright 82 is a shale stirring plow 83, designed to come close to the top surfaces of the car bodies 18 and to turn over and agitate the shale contained thereon, to free the vapors so that they will freely arise through the mass of shale, and so that the various 125 130

1 particles will be turned under against the hot car body 18.

During the time that the shale is progressing through the combustion chamber, 5 the vapor is assisted in separating from the shale, and decomposition of the oil vapors is prevented, if jets of steam are inserted, and for efficiently applying steam to an apparatus of this kind I have provided a 10 steam supply pipe 84, and at certain intervals throughout the length of the combustion chamber are the transversely extended steam pipes 85 connected with the supply pipe 84. Extended downwardly from the 15 pipe 85 are the pipes 86, the lower ends of which are extended forwardly horizontally and are perforated on their under surfaces at 87. Above these perforations is a flat plate 88, tapered from a maximum at its 20 forward end toward the rear end. These plates 88 pass under the body of shale very close to the bottoms 18 of the shale carrying cars, and tend to scrape the shale from the bottom, thus leaving a space. The steam 25 enters this space and must then move laterally under the plate 88 to the sides thereof, where it will pass upwardly through the shale, as this is the line of least resistance.

In devices of this class heretofore, the 30 vapors that arise from the shale have been conducted through suitable pipes to a condenser and there condensed into the form of crude oil, which later has been again treated in such manner as to separate its 35 constituents.

One of the important advantages of my improved apparatus is that the vapors after having once been separated from the shale by heat, are not again commingled and condensed in the form of crude oil, but each of 40 the valuable ingredients of the oil bearing shale, when it has been released from the shale, is vaporized and kept separated from the other ingredients, thus dispensing in a 45 large measure with two separate processes or treatments.

For accomplishing this purpose I have provided a combustion chamber in which the heat is applied principally at the discharge end of the combustion chamber, and then passes under all of the shale bearing cars to the flue. The fresh shale is admitted into the receiving end of the combustion chamber, and when heat is applied the more 50 volatile vapors arise from the shale first. Then after the car has progressed through the combustion chamber to a certain extent, the shale becomes heated to a greater degree and certain other vapors less volatile than 55 the first arise from it, and so on.

I have provided for keeping these different vapors separated, as follows:

Arranged in the vapor chamber is a series 60 of transverse partitions 89, each of which has at its lower end a gas sealing device 90

similar to the one illustrated in Fig. 12, and at the top of each compartment thus formed in the combustion chamber is the vapor discharge pipe 91 leading to a condenser or suitable point of discharge. By means of 70 this arrangement I have found that in the first chamber into which the shales are introduced, the vapor arising therefrom, when condensed, contains a large percentage of 75 gasolene and is substantially free from lubricating oils, paraffin and the like. In the second chamber the vapors that arise therefrom, when condensed, form burning oils containing a large percentage of kerosene, but practically no lubricating oils or paraffin. Whereas, in the last chamber the 80 vapors arising therefrom, when condensed, are composed principally of lubricating oils and paraffin. These various products, when thus separated, may be then purified into 85 commercial form much more rapidly and less expensively than could be done if all of the vapor were condensed into the form of crude oil.

One of the advantages of my improved 90 apparatus is that the oil bearing shales of the smallest or finest character may be effectively treated. In fact, I prefer to reduce all of the shale to a size that will pass through an inch mesh screen, or even smaller 95 in some shales. Furthermore, by having the shale arranged in a very thin layer of exactly uniform thickness, substantially all of the light, volatile oils will pass out of it at the same time and into the first vapor 100 chamber, thus assisting in the separation of the various vapors.

By means of my improved device a continuous process of treating the shale is provided, and all of the valuable products of 105 the shale may be removed from it in much less time than is possible with any prior device.

For these reasons my improved apparatus has a very large capacity, and is substantially automatic in its operation, except, of course, for the operating motors. Practically all the attention that is required by an operator is the caring for the sand seals, which is attended to in the troughs 25 by an 110 operator just prior to the time when the cars are engaged by the lugs 45 on the car driving device.

It is my purpose to utilize my machine for handling a great variety of products having 115 hydro-carbon oils. For instance, I believe my machine could be used in connection with the handling of coal where coke is a by-product.

I claim as my invention:

1. In an apparatus of the class described, the combination of inclosing walls, the lower portion of the space between the walls comprising a combustion chamber, and the upper portion comprising a vapor chamber, a 120

series of material supporting cars arranged for movement in substantially horizontal planes between the combustion chamber and the vapor chamber, and arranged to form a 5 partition between said chambers, sealing devices on the cars and the walls for preventing the passage of products of combustion upwardly past the cars, coacting sealing devices on the successive cars to prevent the 10 passage of said products of combustion upwardly between the cars, and coacting means on the cars and the walls above the first described sealing devices for supporting the cars in their position between the 15 walls.

2. In an apparatus of the class described, the combination of inclosing walls, the lower portion of the space between the walls comprising a combustion chamber, and the upper portion comprising a vapor chamber, a series of material supporting cars arranged for movement in substantially horizontal planes between the combustion chamber and the vapor chamber, and arranged to form a 20 partition between said chambers, sealing devices on the cars and the walls for preventing the passage of products of combustion upwardly past the cars, coacting sealing devices on the successive cars to prevent the 25 passage of said products upwardly between the cars, and coacting means on the cars and the walls above the first described sealing devices for supporting the cars in their position between the walls, and vapor sealing 30 devices between the cars and the side walls.

3. In an apparatus of the class described, the combination of inclosing walls, the lower portion of the space between the walls comprising a combustion chamber, and the upper portion a vapor chamber, a series of material supporting cars arranged for movement in a substantially horizontal plane between the walls, said cars being adapted to form a partition between the 40 combustion chamber and the vapor chamber, partitions extending across the vapor chamber having sealing devices adapted to coact with the cars and the contents thereof at the lower ends of said partitions for dividing the vapor chamber into compartments, means for conducting vapor from the various compartments, and means for supplying maximum heat in the combustion chamber adjacent to the discharge end of 45 the device, the heat supplying means being arranged to supply gradually reduced heat toward the intake end of the device, whereby the incoming material is subjected to the minimum heat and the outgoing material to 50 the maximum heat.

4. In an apparatus of the class described, the combination of an inclosure member, the upper portion of which forms a vapor chamber and the lower portion a combustion 55 chamber, a series of cars arranged to travel

through said inclosure member between the combustion chamber and the vapor chamber, and coacting means on the cars and the inclosure member for supporting the cars during such travel, and means for preventing the passage of products of combustion or vapors from the material in the cars to said supporting means. 70

5. In an apparatus of the class described, the combination of an inclosure member 75 having a combustion chamber at its lower portion and a vapor chamber at its upper portion, cars for carrying material through said inclosure member between the combustion and vapor chambers, a transverse partition in the vapor chamber for separating the vapor chamber into compartments, and means for forming a substantially vapor tight seal between said partition and the top of the layer of material being advanced 80 through the apparatus, said means comprising material leveling devices adjacent to the partition, and a movable sealing member adapted to yieldingly engage the top of the layer of material being driven beneath the 85 partition. 90

6. In an apparatus of the class described, the combination of an inclosure member having a combustion chamber at its lower portion and a vapor chamber at its upper 95 portion, cars for carrying material through said inclosure member between the combustion and vapor chambers, a transverse partition in the vapor chamber for separating the vapor chamber into compartments, means 100 for forming a substantially vapor tight seal between said partition and the top of the layer of material being advanced through the apparatus, said means comprising material leveling devices adjacent to the partition, and a movable sealing member adapted to yieldingly engage the top of the layer of material being driven beneath the partition and means for applying heat to the under side of the material conveying means and 105 for applying a minimum of said heat to the material in the compartments at the intake end of the inclosure, and a maximum of heat to the compartment at the discharge end of 110 the inclosure. 115

7. In an apparatus of the class described, an inclosure, a plurality of cars adapted to travel through said inclosure, and forming a partition between the upper and lower parts of the inclosure, for forming combustion and vapor chambers, means for forming a seal between the cars and the sides of the inclosure, means for forming a seal between the cars while they are traveling through the inclosure, said cars being opened at their 120 ends, and agitator devices projecting downwardly into the path of travel of material in the cars. 125

8. In an apparatus of the class described, an inclosure, a plurality of cars adapted to 130

travel through said inclosure, and forming a partition between the upper and lower parts of the inclosure, for forming combustion and vapor chambers, means for forming 5 a seal between the cars and the sides of the inclosure, means for forming a seal between the cars while they are traveling through the inclosure, said cars being opened at their ends, steam pipes projecting downwardly 10 into the path of the material carried by said cars.

9. In an apparatus of the class described, an inclosure, a series of cars adapted to travel through said inclosure, means for forming a seal between the successive cars, said means comprising a trough-shaped member on each car and a downwardly projecting flange on the adjacent car adapted to enter said trough-shaped member, and a 15 car elevating device designed to elevate one end of each car in a certain position of the car's travel, causing the flange thereon to enter the trough on the adjacent car.

10. In an apparatus of the class described, 20 the combination of an inclosure member, the upper portion of which forms a vapor chamber and the lower portion a combustion chamber, a series of cars arranged to travel through said inclosure member between the 25 combustion chamber and the vapor chamber, and coacting means on the cars and the inclosure member for supporting the cars during such travel, and means for preventing the passage of vapors from the material in 30 the cars to said supporting means.

11. In an apparatus of the class described, 35 the combination of an inclosure member, a plurality of cars for carrying material

through said inclosure member, and for dividing the inclosure member into an upper 40 vapor chamber and a lower combustion chamber, said cars having open ends and having in their bottoms longitudinally arranged, spaced, upwardly extending ribs, 45 agitating and steam supply members including supply pipes extending downwardly through the vapor chamber, and members at the lower end of said supply pipe extending forwardly therefrom, whereby one of said last described members will raise the material between one pair of ribs during the progress of the cars, and permit said material to be dropped over the sides of said last described member, said last described member having steam discharge openings in said 50 sides, whereby steam will be discharged in such a way as to subject all of the material to the action of such steam.

12. In an apparatus of the class described; the combination of inclosing walls, the lower 55 portion of the space between the walls comprising a combustion chamber, and the upper portion comprising a vapor chamber; a series of material supporting cars arranged for movement in a substantially horizontal 60 plane between the combustion chamber and the vapor chamber; sealing devices for forming joints between the successive cars, and between the cars and the walls, whereby the cars themselves form a partition between 65 said chambers, whereby heat may be applied directly to the under sides of the cars, and by radiation through the cars to the material in the cars.

Des Moines, Iowa, July 6, 1918.

HALVER R. STRAIGHT.
